UNITED STATES PATENT OFFICE.

ERNEST A. BICKFORD, OF WORCESTER, MASSACHUSETTS.

SILIPPER-SOLE.

1,150,987.

Specification of Letters Patent. Patented Aug. 24, 1915.

Application filed January 2, 1915. Serial No. 48.

To all whom it may concern:

Be it known that I, ERNEST A. BICKFORD, a citizen of the United States, residing at Worcester, in the county of Worcester and State of Massachusetts, have invented a new and useful Slipper-Sole, of which the following is a specification.

This invention relates to a slipper sole of the type known as the lamb's wool sole.

10 The principal objects of this invention are to provide a construction for this purpose in which the attaching strip for the upper shall have no function except that of supplying means by which the upper can be attached 15 so that it can be made of soft material not likely to be uncomfortable to the wearer; to provide a construction in which the stitching for securing this attaching strip in position will also secure the different parts 20 of the sole firmly together and yet will present no stitches in a position on which any wear comes in use; to provide a construction in which the attaching strip cannot part or become detached from the sole and in which 25 heavy substantial leather can be used to great advantage for the sole instead of the flimsy constructions previously employed and which will admit of great economy in methods of manufacture.

30 Reference is to be had to the accompanying drawings in which—

Figure 1 is a plan of a part of a lamb's wool sole constructed in accordance with this invention showing the attaching strip secured part way around; Fig. 2 is an enlarged side view of a portion of the same; and Fig. 3 is a sectional view transverse to Fig. 2, also showing the upper in position.

The article as shown in the drawings comprises a foundation member *a* of the required shape preferably of leather board or of some other suitable relatively stiff material. This sole is usually covered on the top with a layer of fabric as duck or drill. The 45 outsole *b* is of soft pliable leather attached to the uncovered side, that is, the bottom of the foundation member *a*, and its edges are completely turned up around the edge of the foundation member and are securely attached to its upper or canvas surface, preferably by cementing.

A soft attachment strip *c* is provided along the top of the sole as so far described, that is on the upper surface at the outer 55 edge of the soft leather portion which is inturned. This attachment strip may be of

cord, braid or similar material and is comparatively heavy so that the upper *d* can be stitched to it in a convenient manner, yet it is preferred to make it of a very soft material so that it will not constitute a hard projecting ridge to come against the foot of the wearer. I prefer to use a soft round cord for this purpose and have so shown it. This strip is secured to the sole by over-stitching which comprises inclined or diagonal stitches *e* through the upturned and inturned portion of the outer sole *b* and through the corner of the foundation member *a* and also comprises stitches *e'* on the outer edge of the sole extending up from the bottom of the stitches *e*, and further stitches *e*² at the top. The stitches *e'* are of two kinds, every alternate one being arranged on an incline and the others vertically. The stitches *e*² pass over the top of the attaching strip *c* and together this stitching, which is all made by a well known machine, securely holds the attaching strip in position and also secures it firmly not only to the outer sole but to the foundation member *a* and secures these two parts together also. But it is to be noticed that this stitching emerges from the surface of the sole at a point well above the bottom surface on which the weight of the wearer is borne and which is subjected to wear. This is an important feature because it prevents the stitches themselves being worn off readily in practice and thus adds greatly to the durability of the article.

By placing the attachment strip on the outside upper edge of the sole and securing it there by the inclined over-stitching the member *a*, the soft leather outsole *b*, and the attachment strip *c* are united securely. In this way the attachment strip cannot part or let go, which has been a disadvantage of the draw strings heretofore used in some cases. This construction obviates altogether the necessity of a draw string. The attachment strip cannot become detached from the sole because the diagonal stitching is not presented to the wearing surface of the sole and for this reason this construction presents an important advantage over the usual through and through stitching which is exposed on the wearing surface of the sole and materially reduces the life of the whole article.

On account of the attachment strip serving no other purpose it may be of a soft

nature, such as is best adapted for that purpose alone, thus presenting a soft surface to the foot without any harsh or unyielding substance in it and it is also easy to sew the upper to it by means of stitches *f*. Furthermore, a heavy cord although soft can be used for the attachment strip in this construction. Also the sole *a* can be made of comparatively heavy substantial leather 10 to great advantage. This obviates the flimsy constructions previously employed in many cases which would not permit anything but cheap leather to be used with any economy, on account of the sole being no stronger than 15 its weakest point and consequently giving out when the stitches on the bottom were worn away.

This device permits of great economy in methods of manufacture and furnishes a sole with an attractive edge finish protecting the outer edge of the sole from wear.

The lamb's wool insert is indicated at *g*.

Although I have illustrated and described only a single embodiment of the invention, 25 I am aware of the fact that modifications can be made therein without departing from

the scope of the invention as expressed in the claim, therefore I do not wish to be limited to all the details of construction herein shown and described but

What I do claim is:—

As an article of manufacture, a slipper sole comprising a relatively stiff foundation member, a soft pliable outsole on the bottom thereof having its edges completely turned up around the edge of the foundation member and secured to the upper surface thereof, a large round soft attachment strip lying along the edge on top of said outsole, and a line of stitching securely uniting said foundation member outsole, and attachment strip to each other, said stitching entering the sole along a line just above the bottom thereof.

In testimony whereof I have hereunto set 45 my hand, in the presence of two subscribing witnesses.

ERNEST A. BICKFORD.
